H. T. HARRISON,
ELECTRIC ARC LAMP,
APPLICATION FILED AUG. 23, 1919.

1,355,334.

Patented Oct. 12, 1920.

UNITED STATES PATENT OFFICE.

HAYDN THIES HARRISON, OF WESTMINSTER, ENGLAND.

ELECTRIC-ARC LAMP.

1,355,334.

Specification of Letters Patent.

Patented Oct. 12, 1920.

Original application filed February 4, 1919, Serial No. 274,892. Divided and this application filed August 23, 1919. Serial No. 319,433.

To all whom it may concern:

Be it known that I, HAYDN THIES HARRISON, a subject of the King of Great Britain and Ireland, residing at the city of 5 Westminster, England, have invented Improvements in or Relating to Electric-Arc Lamps, of which the following is a specification.

This invention relates to that class of 10 electric arc lamps in which the temperature of the carbons can be kept down by causing a suitable cooling medium, such as a spirit flame, to play about or come in contact with the carbons.

15 The present invention relates to improved means for supplying and regulating the alcohol or other combustible fluid to the cooling flame, whereby a more efficient cooling effect is produced on the carbons.

20 The invention can advantageously be applied in connection with electric arc lamps of the kind embodying an electric or other rotary device for rotating the carbons of the lamp.

25 In order that the invention may be readily understood reference will be made to the accompanying illustrative drawings in which—

Figure 1 is an elevation showing an electric arc lamp, embodying the invention, this lamp being of the type comprising means for rotating the carbons and such as described in my application for Letters Patent Serial No. 274,892 of which the present application is a division.

Fig. 2 is a part sectional elevation to a larger scale than Fig. 1, of the spirit tank and pump employed for feeding the spirit to the flame.

40 Fig. 3 is an elevation at right angles to Fig. 2 with a portion of the tank removed.

A and B are respectively the positive and negative carbons mounted in heads 1, 1^a, which are supported preferably at an angle 45 to one another, as shown, in stationary parts C of the lamp and are respectively rotated by worm gearing 2, 2^a, and 3, 3^a, operated from a driving wheel 4 rotated by an electric motor 5. The driving wheel 4 is secured on a vertical shaft 6 carrying the worm 2^a of the worm gearing 2, 2^a and is provided at a suitable position with a bevel wheel 7 engaging a bevel wheel 8 fixed to one end of a horizontal shaft 9 that is provided at its other end with a bevel wheel

10. This wheel engages a bevel wheel 11 fixed on a rotatable shaft 12 connected by a flexible coupling 13 to a shaft 14 on to which is fixed the worm 3^a of the worm gearing 3, 3^a, all as described in my said 60 former specification.

To regulate in an efficient manner the amount of alcohol or other liquid (hereinafter referred to as spirit) supplied to the flame used to bathe the carbons A, B for 65 cooling purposes, there is provided a spirit tank from which spirit is delivered by a pump in controllable quantity, it may be past a valve, to a vaporizer arranged to be heated by heat derived by radiation from 70 the electric arc. The spirit tank can be arranged in various positions and spirit delivered therefrom by the pump to the vaporizer in various ways. In the example shown in the drawings, a spirit tank 45 is 75 arranged at the base of the lamp and in the bottom of this tank is a pump immersed in the spirit. 46 is the pump barrel provided with a piston or plunger 47 that is forced downward by a coiled spring 47^a 80 and raised by a crank arm 48 that engages its upper end or head 47^b and is connected to a block 49 carried by a spindle pivoted at 49^a and provided with a vertically adjustable cone 50. This cone, which forms a 85 lever arm, is engaged and oscillated by a lever 51 pivoted on a stud 52 and operated by a cam 53 on the rotary vertical shaft 6 (Fig. 1). By adjusting the cone 50 vertically the stroke of the crank arm 48 and 90 therefore the downward stroke of the pump plunger 47 and the amount of spirit delivered by the pump to the flame can be easily and accurately regulated.

A spirit inlet of any suitable kind can be 95 provided for the pump. Conveniently the inlet may be provided for by means of suitable leakage passages 46^a arranged between the plunger 47 and the barrel 46 of the pump. The pump delivery passage 46^b is 100 controlled by a spring loaded non-return or delivery valve 54 to prevent any return of the spirit delivered by the pump.

The spirit delivered by the pump 46—47 is conveyed by a pipe 56 (Fig. 2) to a vaporizer (Fig. 1) consisting of a small chamber 57 provided with nozzles or jet devices 58 situated adjacent to the arc between the carbon tips so that the heat radiated from the arc and absorbed by the nozzles or jet 110

devices will be conducted to the chamber 57 and utilized to raise its temperature sufficiently high to vaporize the spirit delivered into it.

5. The tank 45 is provided with a suitable filling aperture provided with a tightly fitting screw stopper 55.

What I claim is:—

1. In an electric arc lamp of the kind in 10 which the temperature of the carbons is kept down by the cooling action of a spirit flame, a vaporizer arranged in proximity to the electric arc formed between the carbons so as to become heated by heat derived 60 therefrom and a pump adapted to supply 15 a volatilizable combustible liquid to said vaporizer.

2. In an electric arc lamp of the kind in 20 which the temperature of the carbons is kept down by the cooling action of a spirit flame, a vaporizer arranged in proximity to the electric arc formed between the carbons so as to become heated by heat derived 75 therefrom, a pump for supplying volatilizable combustible liquid to said vaporizer and means for regulating the quantity of liquid supplied by said pump to said vaporizer.

3. In an electric arc lamp of the kind in 30 which the temperature of the carbons is kept down by the cooling action of a spirit flame, a vaporizer arranged in proximity to the electric arc formed between the carbons so as to become heated by heat derived 35 therefrom, a vessel containing combustible liquid, means comprising a pump for supplying liquid in regulated quantity from said vessel to said vaporizer and means for operating said pump from a movable part 40 of the lamp.

4. In an electric arc lamp of the kind in 45 which the temperature of the carbons is kept down by the cooling action of a spirit flame, a vaporizer arranged in proximity to the electric arc formed between the carbons so as to become heated by heat derived therefrom, a vessel containing combustible liquid, tubular connecting means between said vaporizer and vessel, a pump for delivering 50 combustible liquid from said vessel to said vaporizer through said tubular connecting means, means for operating said pump from a movable part of the lamp, and a valve for controlling the flow of liquid 55 through said tubular connecting means.

5. In an electric arc lamp of the kind in which the temperature of the carbons is kept down by the cooling action of a spirit flame, a vaporizer arranged in proximity to the electric arc formed between the carbons 60 so as to become heated by heat derived therefrom, a tank containing combustible liquid, a pump immersed in said liquid and having an inlet adapted to be placed in communication with said tank and an outlet 65 in communication with said vaporizer, a non-return valve controlling said outlet and means for operating the pump from a moving part of the lamp.

6. In an electric arc lamp of the kind 70 in which the temperature of the carbons is kept down by the cooling action of a spirit flame, a vaporizer arranged in proximity to the electric arc formed between the carbons so as to become heated by heat derived 75 therefrom, a tank containing combustible liquid, a pump immersed in said liquid and having an inlet adapted to be placed in communication with said tank and an outlet 80 in communication with said vaporizer, a non-return valve controlling said outlet, means for operating said pump from a moving part of the lamp and means for varying the action of said operating means and the quantity of liquid delivered by said pump. 85

7. In an electric arc lamp of the kind in which the temperature of the carbons is kept down by the cooling action of a spirit flame, means for supplying and controlling spirit to produce such flame, said means 90 comprising a vaporizer arranged in proximity to the electric arc formed between the carbons so as to become heated by heat derived therefrom, a tank containing combustible liquid, a pump immersed in said 95 liquid and having an inlet adapted to be placed in communication with said tank and an outlet in communication with said vaporizer, a non-return valve controlling said outlet, a lever for operating said pump, 100 an endwise adjustable cone connected to said lever, a second lever adapted to operate the first mentioned lever through said cone, and means operated from a movable part of the lamp for operating said second 105 lever.

Signed at Cavendish Sq., London, this 28th day of July 1919.

HAYDN THIES HARRISON.
